UNITED STATES PATENT OFFICE.

WILLIAM H. VOSS, OF DAVENPORT, IOWA.

WRINGER.

Application filed April 9, 1920. Serial No. 372,434.

To all whom it may concern:

Be it known that I, WILLIAM H. Voss, a citizen of the United States, residing at Davenport, in the county of Scott and State of Iowa, have invented certain new and useful Improvements in Wringers, of which the following is a specification.

My invention relates to wringers and more particularly to the tension adjusting and releasing mechanism thereof.

Among the objects of my invention are to provide improved means for the quick release of the upper roll of a wringer in the event that a person's fingers get caught between the rolls or the clothes get bunched so they cannot go through or get wrapped around one of the rolls; to so place the tension means for the wringer roll that a smaller spring may be used than with present constructions and yet have the same or greater tension than in existing structures; to improve upon the construction of the tensioning means; to improve upon the structure of the draining board; to improve upon the mounting of the wringer roll guard; and such further objects, advantages and capabilities as will later more fully appear.

My invention further resides in the combination, construction, and arrangement of parts illustrated in the accompanying drawings, and while I have shown therein a preferred embodiment I desire the same to be understood as illustrative only and not as limiting my invention.

In the accompanying drawings illustrating my invention Fig. 1 is an end view of my improved construction showing the parts in operative position; Fig. 2 is a similar view showing the wringer rolls in separated position; Fig. 3 is an elevation of my improved wringer with a portion of the draining board cut away; Fig. 4 is a section substantially along the plane indicated by the line 4—4 Fig. 3; Fig. 5 is a plan view of my improved structure; Fig. 6 is an expanded view of the tripping and latching mechanism; and Fig. 7 shows a modified form of a portion of the said mechanism.

Referring more in detail to the drawings, 50 1 denotes a pair of frame members having at their upper ends arms or cross heads 2, to which are pivoted at 3, on one side of the wringer roll, a pair of arms 4, notched in their under side to provide space for bearing blocks 5, which receive the ends of the up-

per roll shaft 6. The lower roll shaft 7 is received in corresponding blocks 5^a, as shown most clearly in Fig. 4. These shafts 6 and 7 carry the wringer rolls 8 and 9 and have secured thereto intermeshing gears 10 and 11, as is usual.

The arms 4 extend on the opposite side of bearing blocks 5 from pivot 3 and are provided at their ends with lugs 12 adapted to be engaged by a cross member 13 of yoke 14 pivotally secured at 15 to a bolt 16 having a perforated angular shaped head. This bolt has its free end screw threaded and engaged by a wing nut 17, which is adapted to be screwed thereon to vary the tension of the tensioning spring 18, which has one end resting on a washer surrounding the bolt 16 and its other end resting in a pocket on the under side of arm 2.

Rising from one of the lugs 12 at each side of the machine is a lug 19 having a perforation 20 for the reception of a shaft 21. This shaft is pivoted in the perforations in the lugs 19 and has secured thereto an operating arm 22 and a sleeve 23 which has projecting from one side thereof a finger 24 adapted to enter the slot between a pair of lugs 12, as shown in Figs. 4 and 6. The structure just described can be modified as shown in Fig. 7 by forming 85 the hand lever 22 integral with the sleeve 23 and tripping lug 24, which will reduce materially the cost of construction of this part of the device. It is, of course, understood that whichever form of construction 90 is used at one side of the machine it will be necessary to have at the other side of the machine a tripping device, which will preferably be like that shown at 23, 24 in Fig. 6.

In order to hold the shaft 6 in proper position when latches 14 are released, slotted members 25 and 26 are provided. The slots in these members pass down over shaft 6 and, in operative position, enclose also shaft 7. The former of these members is a gear casing which encloses gears 10 and 11 referred to above. Each of these members carries a lug 27, into which is screwed a bolt 28, held in place by a nut 29. These 105 bolts 28 pass through slotted angular plates 30 secured to arms 4, as shown in the drawings, or thru perforated lugs made integral with these arms, if preferred. In the form just suggested there would be both pivotal, 110

and relative sliding motion as in the form shown.

In the form of my device here shown arms 2 are provided near pivot 3 with lugs 31 to 5 limit the pivotal motion of arms 4, as shown in Fig. 2, but these lugs 31 may be omitted if desired or considered preferable, so that arms 4 may be swung through more than 90 degrees. If this form of construction is 10 used it will probably be found desirable to provide means to prevent wringer shaft 6 from dropping out of the slot in members 25 and 26. For this purpose any suitable construction may be employed, but it will 15 preferably be a movable latch member on said members 25 and 26. However, a fixed lug may be employed on one of these and a movable latch member on the other.

One of the possible variations of the latch 20 member 14 of which I have thought is to have a sleeve loosely enough mounted on rivet 13 so as to have easy pivotal motion thereon, thereby reducing the friction incident to the sliding of member 13 on lugs 12. 25 I have considered and may use other forms of construction of bolt 16 and yoke 14.

The frame members 1 are connected and held in place by a rod 32 shown as provided at its opposite ends with nuts. Near this 30 rod 32 frame members 1 are provided with perforations into which extend pintles 33 of the draining board 34, to the underside of which is secured a spring 35 having a downwardly projecting portion 36 adapted to 35 ride over rod 32, as the draining board is rocked on its pintles 33. The projection or hump 36 will hold the draining board in adjusted position so as to drain water to one side or the other of the wringer, unless a 40 sufficient amount of force is exerted upon the board to overcome the strength of the spring, whereupon the board may be rocked to its other extreme position. It will be seen from the drawings that the edges of the 45 draining board are reinforced and made safe for clothing by rolling the same, and that the sides are turned up to form flanges to which the pintles 33 may be secured, and which serve as means to prevent the water 50 from running off the sides of the draining board. The bottom ends of the frame members 1 may be provided with any suitable attaching means 37 for attaching the wringer to a support.

55 Rods 38 and 39 pass thru alining perforations in arms 2, in which they are pivotally mounted. Carried by these rods 38 and 39 are plates 40 and 41, which have their inner edges bent under and resting close to the 60 line of contact of the wringer rolls. These plates 40 and 41 have near their ends flanged guard members 42, which prevent articles being run thru the wringer from spreading out laterally and getting into the gears 10 and 11 or against members 25 and 26.

These members 42 also prevent water dripping from the clothes as they are put into the wringer from spreading out laterally and dropping down beyond the edges of the draining board. It will be seen from the 70 above that plates 40 and 41 may be rotated on their pivots and be turned entirely away from the wringer rolls if desired for any purpose. It is also obvious that a construction such as described will guide the clothes 75 between the wringer rolls so that it will be extremely easy to properly feed the clothes therethrough. It also is apparent that the bent over edges of the plates 40 and 41 will have a tendency to prevent articles of 80 clothing from winding up on the lower wringer roll and to strip them therefrom in the event that they should start to do so.

It is, of course, understood that the specific description of structure set forth above 85 may be departed from without departing from the spirit of my invention as set forth in this specification and the appended claims.

Having now described my invention, I 90 claim:

1. In a wringer, the combination of co-acting rolls, relatively movable roll supporting members, said rolls being rotatable in said members, means normally holding 95 said rolls together, said means comprising a resiliently movable part on one of said members, a projection on the other of said members, a holding element pivotally connected to said part and engaging said projection for holding said rolls together, and manually movable means on one of said members and movable to disengage said holding element from said projection. 100

2. In a wringer, the combination of co-acting rolls, relatively movable roll supporting members, said rolls being rotatable in said members, means normally holding 105 said rolls together, said means comprising a resiliently movable part on one of said members, a projection on the other of said members, a holding element pivotally connected to said part and engaging said projection for holding said rolls together, and manually movable means pivotally connected to one of said members and operable to disengage said holding element from said projection. 110

3. In a wringer, the combination of co-acting rolls, relatively movable roll supporting members, said rolls being rotatable in said members, means normally holding 115 said rolls together, said means comprising a resiliently movable part on one of said members, a projection on the other of said members, a holding element pivotally connected to said part and engaging said projection for holding said rolls together, and a lever connected to the member having 120 said projection and movable to disengage 125 said projection and movable to disengage 130

said holding element from said projection.

4. In a wringer, an arm adapted to be pivotally connected at one end to a roll supporting member and carrying intermediate its ends a roll bearing, said arm having at its opposite end a lug for engagement by a latch member, an upstanding perforated lug on the first named lug, a latch member engaging said first named lug, and trip mechanism for releasing the latch member from the first named lug, said trip mechanism being pivoted in said second named lug.

5. In a wringer, a frame, a roll journaled in said frame, said frame having projections extending laterally on opposite sides of said roll, arms pivoted on a pair of said projections and adapted to hold a wringer roll in engagement with said first named roll, an upstanding lug adjacent one end of each of said arms, a shaft pivoted in said lug and carrying trip mechanisms, latches resiliently held in connection with the frame, adapted to engage the arms and to be engaged by the trip mechanisms to be thereby released from the arm.

6. In a wringer, an arm carrying a roll

approximately centrally, said arm extending transversely of the roll, an arm pivoted at one end to one end of the first named arm and carrying a roll to co-operate with the first named roll, said rolls each carrying a gear, and a gear casing connected to the pivoted arm and enclosing the said gears.

7. In a wringer, tensioning means for adjusting the pressure on articles put thru the wringer, comprising a support for the wringer roll, an angular headed bolt passing thru the support and having in its head a perforation, a yoke, means passing thru the yoke and the perforation to pivotally connect the former to the bolt, a spring surrounding the bolt and engaging the frame, and means adjustable on the bolt and engaging an end of the spring so that the tension on the spring may be varied.

In witness whereof I hereunto subscribe my name to this specification in the presence of two witnesses.
